(57) **CLAIM**

The ornamental design for a LED flexible wand, as shown and described.

DESCRIPTION

FIG. 1 is a perspective view of the LED flexible wand showing my new design; wherein the cutting plane line indicates that the design in the figure is shortened for display purpose. FIG. 2 is a right plan view thereof; wherein the cutting plane line indicates that the design in the figure is shortened for display purpose.

FIG. 3 is a left plan view thereof; wherein the cutting plane line indicates that the design in the figure is shortened for display purpose.

FIG. 4 is an upward plan view;

FIG. 5 is a downward plan view.

FIG. 6 is a front plan view thereof; wherein the cutting plane line indicates that the design in the figure is shortened for display purpose; and,

FIG. 7 is a back plan view thereof; wherein the cutting plane line indicates that the design in the figure is shortened for display purpose.
